CLAIM

The ornamental design for a water bottle for small animals, as shown and described.

DESCRIPTION

FIG. 1 is a perspective view, enlarged with respect to the other views, taken from the front and left side of a water bottle for small animals showing my new design; FIG. 2 is a front elevational view thereof; FIG. 3 is a right side elevational view thereof, the left side being a mirror image of the right side shown; FIG. 4 is a rear elevational view thereof; FIG. 5 is a bottom plan view thereof; FIG. 6 is a top plan view thereof; and, FIG. 7 is a top perspective view thereof.

FIG. 1

FIG. 2**FIG. 3****FIG. 4****FIG. 5****FIG. 6****FIG. 7**
